DRIVING-BOX MOUNTING.

Application filed August 25, 1926. Serial No. 131,452.

The present invention relates to driving boxes, and more particularly to the mounting of the same and the construction of the frame pedestal shoes which are positioned between the driving box and the jaws of the frame pedestal.

The invention also relates to means for taking up lateral play between the wheels and driving box and for providing an improved construction which will assist in securing the pedestal binder to the frame.

Although the invention is intended primarily, for use with locomotive driving boxes, it is also applicable to the wheel and axle construction of engine and trailing trucks and the like.

The driving box is ordinarily positioned between two jaws of a frame pedestal and a binder extends between the jaws below the box which has end flanges disposed on opposite sides of the jaws. Between the driving box and each pedestal jaw is arranged a shoe which has flanges extending on opposite sides of the pedestal jaws to prevent lateral movement between the shoes and frame. One of these shoes is usually of wedge formation, or has interposed between the same and the pedestal jaw a wedge element which is vertically adjustable to take up wear.

The flanges on the shoes frequently break off and replacement involves considerable labor since it is necessary to drop the binder. This breakage is frequently due to the side thrust of the engine which develops particularly in taking curves, and defective adjustment of the compensating wedge, which is ordinarily provided with one of the shoes, or to improper vertical adjustment of the shoe itself when it is of wedge formation.

The present invention seeks to provide a shoe construction which will prevent wear upon the frame and which will include more rugged and durable shoes.

The invention also seeks to provide means for readily taking up excess lateral motion between the locomotive wheel and the driving box. When excess motion between a locomotive wheel and its driving box develops, it must be immediately reduced within certain limits. Heretofore, it has been necessary, in order to reduce this lateral play, to remove the wheel and axle from the locomotive, which entails considerable expense and delay.

The invention seeks to provide an improved shoe and wedge construction which will facilitate taking up of lateral play and render unnecessary the removal of the wheel and axle.

Briefly, the invention consists in providing relatively flat shoes instead of the usual shoes which are substantially U-shaped in cross section and have flanges extending on opposite sides of the pedestal jaws. Upon the frame at each pedestal jaw is provided means, preferably in the form of elongated strips, which extend outwardly beyond the face of the jaws and at each side of the shoes, to retain the latter against lateral movement. These strips extend downwardly at the side of each pedestal jaw, between the frame and the driving box flanges and vertical movement of the driving box in the pedestal causes wear only upon the shoes and the strips, which may be readily replaced. To take up wear one of the shoes may be formed as a wedge or may have positioned behind the same against the pedestal jaw a vertically adjustable wedge element. When the vertical strips which retain the shoes in position become worn, they may be readily replaced and thus there is no need for filling out the frame which is fully protected by the retaining strips.

Furthermore, the strips are preferably constructed of different thickness from one another so that simply by transposing them it is possible to effect a lateral adjustment of the driving box, and thereby take up any lateral motion between the wheel hub and the driving box.

The above and other features and objects of the invention will become clearer as the description proceeds in connection with a preferred embodiment shown in the accompanying drawings, wherein—

Figure 1 is a partial elevation and partial sectional view on the line 1—1 of Figure 3.

Figure 2 is a vertical sectional view on the line 2—2 of Figure 1.

Figure 3 is a horizontal sectional view on the line 3—3 of Figure 1.

Referring to the drawings for a more detailed description, the invention is shown as applied to the frame of the locomotive having the usual spaced pedestal jaws 10, 11, the latter having an inclined face 11'. Between the jaws is positioned a driving box 12 enclosing the axle 13 which carries

the wheel 14. The driving box has circumferential end flanges 15 on opposite sides of the frame jaws, and is retained in the pedestal by a binder 16 secured to the frame as by means of bolts 17. The parts thus far described are of usual construction, and will be immediately recognized by one skilled in the art.

Between the driving box and each pedestal jaw are positioned shoes 18, 19, for the purpose of preventing wear upon the frame and driving box as the latter moves vertically in the pedestal as will be understood. Each shoe is relatively flat as distinguished from the usual shoe which is substantially U-shaped in cross section and has flanges fitting opposite sides of the pedestal jaws. In lieu of such flanges there is provided retaining means, preferably in the form of elongated strips 20 arranged on opposite sides of each pedestal jaw and extending beyond the face of the jaw toward the driving box. These strips receive the shoes therebetween and prevent lateral movement of the shoes. It will be observed further that they are arranged between the driving box flanges 13 and pedestal jaws so that any wear resulting from vertical movement of the driving box takes place upon the strips and not upon the frame, the strips being held rigidly on the frame against movement.

For the purpose of securing the strips they may be either bolted to the frame, or, as illustrated in the drawings, extended upwardly and laterally over the top of the frame to provide supporting shoulders 22 and juxtaposed lugs 22' connected by a bolt 23. The strips may be also lengthened downwardly to provide portions 24 adapted to receive a binder supporting element 25 in the form of a wedge which extends through the strip portions 24 and has a threaded terminal 25 receiving a locking nut 26. This construction provides an emergency support for the binder should the retaining bolts break off.

It will be observed that the outer strips are somewhat thinner than the inner ones, which is their relative position when first installed. This arrangement is adopted in order to permit of outward adjustment of the driving box toward the wheel when excess lateral motion develops between the wheel and driving box due to wear upon the wheel hub liner 27 and the driving box liner 28. By simply removing the strips and transposing the two pairs on opposite sides of the engine the thicker strips will be placed between the outer flanges of the driving boxes and the frame, thus throwing the driving boxes outwardly a sufficient distance to take up any play which may have developed. To remove the strips it is simply necessary to withdraw the bottom wedge 25 and draw them upwardly. This is, of course,

a much simpler and less expensive operation than the usual one involving dropping of the wheels and axle and replacement of the wheel hub liner and the box liner. When installed, they provide additional supports for the binder, due to the provision of the connecting wedge 25 between their lower ends and their connection to the frame which, in the present instance, is a very rugged one due to the inwardly turned shoulder portions which overlie the frame.

In the present embodiment of the invention the same is shown as used in connection with a shoe 19, which, instead of being itself formed as a vertically movable wedge element to cooperate with the inclined pedestal jaw 11' has positioned between it and the jaw face 11' a vertically adjustable wedge 29. This wedge at its lower end has connected therewith an adjusting bolt 30 extending through the binder, and as will be understood, is provided for the purpose of maintaining the shoe closely against the driving box so that only vertical movement of the latter may take place. It will be understood, however, that the invention is applicable to either this type of wedge construction or that in which the shoe and wedge are of integral construction.

The invention has a number of very marked advantages over the ordinary construction, wherein the shoes are substantially U-shaped in cross section. These advantages, briefly, are:

1. The elimination of shoe breakage which is the cause of considerable repair work upon locomotives.

2. The elimination of virtually all wear upon the sides of the frame pedestal jaws, since the strips cannot move with the shoes should any vertical movement of these take place due to defective adjustment of the wedge.

3. Facilitates taking up of excess lateral motion between the wheel and driving box by eliminating the necessity for dropping the entire wheel and axle; and

4. Provides an additional support for the binder to take the place of the securing bolts should the latter break off.

The invention is not limited to the details of construction illustrated and described, since it may be modified considerably without departing from its essential features as set forth in the following claims:

We claim:

1. In combination with a driving box and a frame receiving the same between spaced pedestal jaws, of detachable shoe retaining strips supported on the frame on opposite sides of one pedestal jaw and projecting beyond the face of said jaws toward the other jaw, a relatively flat shoe element interposed between the box and the pedestal jaw, said shoe being positioned between the

- projecting portions of said strips, and a relatively flat wedge element between the box and the other pedestal jaw, and a pair of detachable shoe retaining strips supported 5 on the frame on opposite sides of said wedge element and projecting beyond the face of the pedestal jaw toward the first mentioned jaw, whereby to hold the wedge element against lateral movement.
- 10 2. In combination with a driving box and a frame receiving the same between spaced pedestal jaws, of detachable shoe retaining strips supported on the frame on opposite sides of one pedestal jaw and projecting beyond the face of said jaws toward the other jaw, a relatively flat shoe element interposed between the box and the pedestal jaw, said shoe being positioned between the projecting portions of said strip, and a relatively flat wedged element between the box and the other pedestal jaw, and a pair of detachable shoe retaining strips supported on the frame on opposite sides of said wedge element and projecting beyond the face of the pedestal jaw toward the first mentioned jaw, whereby to hold the wedge element against lateral movement, each member of said two pairs of strips being of substantially uniform thickness throughout 20 its length and the strips on opposite sides being of different thickness from one another, whereby transpositioning of the strips will adjust the box relative to the frame.
- 25 3. In combination with a driving box, a frame receiving the same between spaced pedestal jaws and a pedestal binder extending between the jaws and secured to the frame, of detachable shoe retaining strips positioned on opposite sides of the frame and secured to the same, said shoe retaining strips extending beyond the face of one of the pedestal jaws, and a relatively flat shoe element positioned between said strips and held thereby against lateral movement, said strips being extended upwardly and laterally over the frame.
- 30 4. In combination with a driving box, a frame receiving the same between spaced pedestal jaws and a pedestal binder extending between the jaws and secured to the frame, of detachable shoe retaining strips positioned on opposite sides of the frame and secured to the same, said shoe retaining strips extending beyond the face of one of the pedestal jaws, and a relatively flat shoe element positioned between said strips and held thereby against lateral movement, said strips being extended upwardly and laterally over the frame, and being connected above the frame.
- 35 5. In combination with a driving box and a frame receiving the same between spaced pedestal jaws, of detachable shoe retaining strips each of substantially uniform thick-
- ness supported on the frame on opposite sides of the same and projecting beyond the face of one of the pedestal jaws toward the other jaw, and a relatively flat shoe positioned between said strips and held thereby against lateral movement, the strips on opposite sides being of different thickness from one another.
- 40 6. In combination with a driving box and a frame receiving the same between spaced pedestal jaws, of detachable shoe retaining strips each of substantially uniform thickness supported on the frame on opposite sides of the same and projecting beyond the face of one of the pedestal jaws toward the other jaw, and a relatively flat shoe and wedge positioned between said strips and held thereby against lateral movement, the strips on opposite sides being of different thickness from one another.
- 45 7. In combination with a driving box, a frame receiving the same between spaced pedestal jaws and a pedestal binder extending between the jaws and secured to the frame, of detachable shoe retaining means positioned on opposite sides of the frame and secured to the same, said shoe retaining means extending beyond the face of one of the pedestal jaws, and a relatively flat shoe element positioned between said means and held thereby against lateral movement, said means extending downwardly beneath the pedestal binder and being adapted to support the latter.
- 50 8. In combination with a driving box, a frame receiving the same between spaced pedestal jaws and a pedestal binder extending between the jaws and secured to the frame, of detachable shoe retaining strips positioned on opposite sides of the frame and secured to the same, said shoe retaining strips extending beyond the face of one of the pedestal jaws, and a relatively flat shoe element positioned between said strips and held thereby against lateral movement, said strips extending downwardly beneath the pedestal binder and being adapted to support the latter.
- 55 9. In combination with a driving box, a frame receiving the same between spaced pedestal jaws and a pedestal binder extending between the jaws and secured to the frame, of detachable shoe retaining strips positioned on opposite sides of the frame and secured to the same, said shoe retaining strips extending beyond the face of one of the pedestal jaws, and a relatively flat shoe element positioned between said strips and held thereby against lateral movement, said strips extending downwardly beneath the pedestal binder and being adapted to support the latter, and being extended upwardly and laterally over the frame.
- 60 10. In combination with a driving box, a frame receiving the same between spaced

pedestal jaws and a pedestal binder extending between the jaws and secured to the frame, of detachable shoe retaining strips positioned on opposite sides of the frame and secured to the same, said shoe retaining strips extending beyond the face of one of the pedestal jaws, and a relatively flat shoe element positioned between said strips and held thereby against lateral movement, said strips extending downwardly beneath the pedestal binder and being adapted to support the latter, said strips being extended upwardly and laterally over the frame, and being connected to one another above the frame.

11. In combination with a driving box and

a frame receiving the same between spaced pedestal jaws, of detachable wedge retaining strips each of substantially uniform thickness supported on the frame on opposite sides of the same and projecting beyond the face of one of the pedestal jaws toward the other jaw, and a relatively flat wedge element positioned between said strips and held thereby against lateral movement, the strips on opposite sides of the frame being of different thickness from one another, and being adapted to be transposed.

In testimony whereof we have hereunto set our hands.
